R. MURRAY

CONCRETE MOLD

Filed May 24, 1924

Patented May 19, 1925.

1,538,578

UNITED STATES PATENT OFFICE.

RICHARD MURRAY, OF NEW YORK, N. Y.

CONCRETE MOLD.

Application filed May 24, 1924. Serial No. 715,522.

To all whom it may concern:

Be it known that I, RICHARD MURRAY, a citizen of the United States, and residing at New York, in the county of New York and State of New York, have invented certain new and useful Improvements in Concrete Molds, of which the following is a specification, such as will enable those skilled in the art to which it appertains to make and use the same.

This invention relates to concrete molds and particularly to molds of this class designed for use in molding bricks or blocks to be mounted one upon another in the construction of a building wall and the like and further to a mold which may be used in forming a wall construction by intermittently forming predetermined portions of the wall structure by said mold; and the object of the invention is to provide a device of the class and for the purpose specified by means of which the representation of a plurality of bricks or blocks may be formed in one molded body, and whereby apertures may be formed therein, means being employed whereby a single brick section or a predetermined number of brick sections may be formed whenever desired; a further object being to provide a mold of the class and for the purpose specified composed of separate detachably and adjustably connected parts with means for holding the separate parts in predetermined spaced relation; a further object being to provide the end portions of the mold with means whereby a continuous series of molded sections may be formed on a wall structure; a still further object being to provide means for holding the several parts of the mold in operative position and whereby parts thereof may be automatically separated in the operation of releasing the holding means; and with these and other objects in view, the invention consists in a device of the class and for the purpose specified, which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a plan view of one form of mold which I employ, with part of the construction broken away and in section.

Fig. 2 is a transverse sectional view of the mold shown in Fig. 1 on an enlarged scale and with part of the construction broken away.

Fig. 3 is a longitudinal sectional view through one end portion of the mold shown in Fig. 1 and showing a modification.

Fig. 4 is a partial section on the line 4—4 of Fig. 3.

Fig. 5 is a diagrammatic view showing another use of the mold shown in Figs. 1 and 2 of the drawing, with part of the construction omitted, the mold being shown in longitudinal section and mounted upon a wall construction partially formed by the use of said mold; and,

Fig. 6 is a section on the line 6—6 or Fig. 5, and on an enlarged scale.

In the construction shown in Figs. 1 and 2 of the drawing, my improved mold is composed of a bottom or base member 10 which may be composed of metal if desired, but in the construction shown is composed of a strip of wood faced by a metal sheet 11. Side mold plate members 12 and 13 are employed in connection with the base member 10 and may be composed of a suitably constructed metallic body, but in the construction shown are composed of wood strips faced on their inner faces by sheets of metal 14. The member 13 is provided with inwardly projecting rib members 15 forming mold faces which represent on the concrete body formed by the mold or in one face thereof, brick sections as diagrammatically illustrated in Fig. 5 of the drawing.

Pivotedly mounted in connection with the top face of the member 12 substantially centrally thereof is a gage bar 16 having spaced apertures 17 at its free end portion which are adapted to operate in connection with a headed lock member 18 in connection with the member 13 as clearly shown in Figs. 1 and 2. The gage bar 16 operates to hold the upper end portions of the members 12 and 13 in predetermined spaced relation.

A clamp 19 is employed in connection with the central part of the mold and for forcing the members 12 and 13 inwardly to retain the same in proper position. One jaw, the stationary jaw 20 of the clamp 19, is adapted to seat in a keeper 21 secured to the outer face of the member 12, while the adjustable and movable jaw 22 of the clamp, 110 engages a similar keeper 23 on the outer face of the member 13. With this construction,

by releasing the jaw 22, the members 12 and 13 will be automatically separated to free themselves from the molded body of concrete or similar material. On inner adjacent faces of the end portions of the members 12 and 13 are U-shaped guide members 24 to receive and support end walls or gates 25 and 26 which form a finish to the ends of the body to be formed in the mold, but these 10 end walls or gates may be spaced intermediate the two shown in Fig. 1 of the drawing in the manner shown in Figs. 3 and 4 of the drawing wherein a gate or wall 27 is shown, whereby a single brick size body may be formed or a body of any number of brick size formed, as may be desired.

At the end portion of the mold, provided with the gate 25 as shown in Fig. 1, is employed a transverse bar 28 which is secured to the top face of the member 13 and passes through a keeper 29 secured to the top face of the member 13, while the other end portion of the mold is provided with a bar 30 secured to the outer end of the member 12 adjacent to the lower end portion thereof and the bottom edge of which is in line with the top face of the bottom member or base 10 of the mold, and the bar 30 passes through a keeper 31 secured to the member 13 and positioned thereon to retain the bar in the position above set out.

I also employ a core member 33 in the form of an elongated bar 34 having on its lower face a plurality of depending and 35 equally spaced core pieces 35 adapted to form apertures in the bodies formed by the mold, and as shown in Figs. 1 and 2 of the drawing the core pieces 35 rest upon the base 10, and the core member 30 is retained 40 in proper position by transverse bars 36 positioned adjacent the end portions thereof and which cooperate with keepers 37 mounted upon the members 12 and 13.

The mold shown in Figs. 1 and 2 of the drawing is designed primarily for use in forming elongated blocks or sections of concrete, which when formed represent a plurality of brick or block sections formed in one unitary body, it being understood that 50 the concrete is inserted into the mold, when the parts thereof are assembled, through the spaces which open outwardly through the top thereof and when the concrete section has been formed and set sufficiently, the gage 55 bar is moved into inoperative position, the clamp operating to separate the members 12 and 13, and the concrete member removed, it being understood that the rods 28 and 30 perform no function in the formation of 60 concrete block sections, as above set out. It will also be understood that the clamp 19 is removable from the keepers 21 and 23.

In the construction shown in Figs. 3 and 4, the gate or wall 27 is provided with a 65 longitudinally directed core piece 27^a de-

signed to form an aperture in one end of a brick or block formed within the space between the gate or wall 25 and the gate or wall 27.

In addition to using my improved mold 70 for forming separate brick or block sections as above set out, the same may be used in the construction of a wall or other concrete structure, in which event, the bottom or base member 10 of the mold is not employed; 75 and in this use of the mold, the members 12 and 13 form side mold faces, which rest and bear upon the inner and outer faces of a previously formed wall or concrete structure, which however has been formed by the 80 said mold, and in Fig. 5 of the drawing, the wall or concrete structure is shown at 38. In working from left to right, the mold as shown in the drawing is employed, and the bar 28 rests upon the top of a previously 85 formed portion of the wall as indicated at the left of Fig. 5 of the drawing, while the bar 30 rests upon the top of the wall upon which the new section is to be formed, as shown at the right of Fig. 5 of the drawing, 90 it being understood that said rods retain the mold in proper position or longitudinal alignment. The clamp 29 is used for compressing the members 12 and 13 and holding the same in firm engagement with the wall 95 structure 38 in the same manner as the engagement of said members with the base member 10 in the first named use of the mold, and the gage bar 16 serves to hold the top portions of the members 12 and 13 in 100 proper spaced relation. With the use of the mold as shown in Figs. 5 and 6 of the drawing, the core pieces 35 extend downwardly into the apertures 38^a previously formed in the wall structure, as clearly illustrated in 105 Fig. 5 of the drawing, whereby continuous passages are formed through the wall structure 38.

After the mold has been mounted in proper position as indicated in Figs. 5 and 110 6 of the drawing, the concrete is poured thereinto, and allowed to set sufficiently to permit of the removal of the mold parts, which will be a comparatively short time, especially when quick setting cement or concrete is employed, and the mold may be removed and shifted to form another wall section. It will also be apparent that in the above operation or use of the mold shown in Fig. 5 of the drawing, the end wall 25 as 115 well as the guide members 24 are removed at the left hand end portion of the mold and the wall 26 only is employed. In working from right to left however or in the reverse direction, a mold will be employed in which the rod 28 is at the right of the mold and the rod 30 at the left of the mold and the end wall 26 will be removed together with the guide members therefor. In other words, the mold will be made up in lefts 120 125 130

and rights, and in the construction of a building wall or other concrete body structure, it will be apparent that any desired number of the molds may be employed, and 5 the molds may be modified to form curvatures in the wall or concrete body structure as well as corner formations, the distinctive novelty of my invention residing in the provision of a portable mold device which 10 may be quickly mounted in position, and shifted into new positions in the formation of a wall.

In the last named use of the mold, it will be understood that the inwardly projecting 15 rib members 15 cooperate with the grooves previously formed by said rib members in forming predetermined sections of a wall; and in Fig. 6 of the drawing, I have shown 20 one of the rib members engaging the top recess of the wall structure 38.

It will be understood that while I have shown certain details of construction for carrying my invention into effect and especially in the formation of the mold parts 25 proper and the means for operating the same, and for retaining the same in spaced relation, I am not necessarily limited to the details of construction herein shown and described, and various changes therein and 30 modifications thereof, may be made within the scope of the appended claims without departing from the spirit of my invention or sacrificing its advantages.

Having fully described my invention, 35 what I claim as new and desire to secure by Letters Patent, is:

1. A mold of the class described comprising two substantially parallel mold members, means whereby said members may be 40 retained in spaced relation, means for moving said members toward and from each other, and means for supporting the end portions of said members in connection with supports arranged at different levels.

2. A mold of the class described comprising two substantially parallel mold members, means whereby said members may be 45 retained in spaced relation, means for moving said members toward and from each other, and means for supporting the end portions of said members in connection with supports arranged at different levels, and for properly alining said members on said supports.

3. A mold of the class described comprising two substantially parallel mold members, means whereby said members may be 50 retained in spaced relation, means for moving said members toward and from each other, end members for supporting the end portions of said mold members in connection with predetermined supports and for properly alining said members on said supports, said mold members being adjustable 55 on said end members, and means positioned

between said members for forming finished ends to the bodies formed by said mold.

4. A mold of the class described comprising two substantially parallel mold members, means whereby said members may be 60 retained in spaced relation, means for moving said members toward and from each other, end members for supporting the end portions of said mold members in connection with predetermined supports and for 65 properly alining said members on said supports, said mold members being adjustable on said end members, means positioned between said members for forming finished ends to the bodies formed by said mold, and 70 a core member mounted in connection with said first named members and suspended therebetween.

5. A mold of the class described comprising two substantially parallel mold members, means for adjustably retaining said 75 members in predetermined spaced relation, means coupled with said members and independent of said last named means for moving one of said members toward and 80 from the other and for retaining said members rigidly in a predetermined adjusted position, and means at the end portion of said members for supporting a mold in connection with a predetermined support having 85 surfaces arranged at different levels.

6. A mold of the class described comprising two substantially parallel mold members, means for adjustably retaining said 90 members in predetermined spaced relation, means coupled with said members and independent of said last named means for moving one of said members toward and 95 from the other and for retaining said members rigidly in a predetermined adjusted position, means at the end portion of said members for supporting a mold in connection with a predetermined support having surfaces arranged at different levels, and 100 means at the end portions of said members whereby finished end walls may be formed by the mold at either or both end portions thereof.

7. A mold of the class described comprising two substantially parallel mold members, means for adjustably retaining said 105 members in predetermined spaced relation, means coupled with said members and independent of said last named means for moving one of said members toward and from the other and for retaining said members rigidly in a predetermined adjusted position, means at the end portions of said members for supporting a mold in connection with a predetermined support having 110 surfaces arranged at different levels, means at the end portions of said members whereby finished end walls may be formed by the mold at either or both end portions thereof, a core mounted in connection with the top walls of said members 115 120 125 130

and positioned centrally therebetween, and means for retaining said core against displacement.

8. A mold of the class described comprising two substantially parallel mold members of predetermined length and height, a bar secured to one of said members and adjustably connected with the other of said members for supporting said members in spaced relation, means involving an adjustable element for moving said members into predetermined spaced relation, and supporting members at the end portions of said mold members, one of said supporting members being adjacent the upper end of the mold members and the other adjacent the lower end thereof.

9. A mold of the class described comprising two substantially parallel mold members of predetermined length and height, a bar secured to one of said members and adjustably connected with the other of said members for supporting said members in spaced relation, means involving an adjustable element for moving said members into predetermined spaced relation, supporting members at the end portions of said mold members, one of said supporting members being adjacent the upper end of the mold members and the other adjacent the lower end thereof, and means for detachably supporting a transverse wall within and between said mold members.

10. A mold of the class described comprising two substantially parallel mold members of predetermined length and height, a bar secured to one of said members and adjustably connected with the other of said

members for supporting said members in spaced relation, means involving an adjustable element for moving said members into predetermined spaced relation, supporting members at the end portions of said mold members, one of said supporting members being adjacent the upper end of the mold members and the other adjacent the lower end thereof, means for detachably supporting a transverse wall within and between said mold members, and means on said mold members for supporting a core between the adjacent faces of said members.

11. A mold of the class described comprising two substantially parallel mold members of predetermined length and height, a bar secured to one of said members and adjustably connected with the other of said members for supporting said members in spaced relation, means involving an adjustable element for moving said members into predetermined spaced relation, supporting members at the end portions of said mold members, one of said supporting members being adjacent the upper end of the mold members and the other adjacent the lower end thereof, said supporting members involving bars secured to one of said mold members and adjustable in the other mold member, means for detachably supporting a transverse wall within and between said mold members, and means on said mold members for supporting a core between the adjacent faces of said members.

In testimony that I claim the foregoing as my invention I have signed my name this 21st day of May, 1924.

RICHARD MURRAY.
